assignors to

Fuller, Warren & Morrison of the same place

Letters Patent No. 823, Dated Aug. 5th 1856.

The schedule referred to in these Letters Patent and making part of
the same.

To all whom it may concern:

Be it known that we Samuel Pierce and J. J.,
Dulley, of Troy, in the County of Rensselaer, and State of New York,

Dec. 823

have invented or produced a new and original design for a Cook Stove, which we call the "Pride of America", and we do hereby declare that the following is a full, clear and exact description of the same, reference being had to the annexed perspective drawing, and the letters of reference marked thereon, forming part of this specification.

The description of our design of Cook Stove, is as follows. *No. 1*; A is the top plate, having an ornamental border (a a) B, is the upper front plate with the fire doors C, C, which have their edges formed into mouldings (b, b) and upon the panels is the ornament C, composed of a shield, liberty cap, national ensigns, and cannons. D, is the hearth with an ornamental border (C). E, is the lower front plate, having the mouldings (d). F, is the bottom plate, with the ornamental mouldings (e), around its edges. G is the leg, having scroll edges (f) and upon its face the ornament (g). H, is the jamb plate with the moulding (h) around its edges, I, is the end fire door, with the moulding (i) and ornament (j) upon its panel, J & K are oven doors having respectively the mouldings (k k) for the frames, arranged upon the panel of the door J, is the ornament (l), and arranged upon the panel of the door K, is the shield (m) eagle (m) national ensigns (o) cannons (p p) liberty caps (q q) scrolls (r r) - sun (s), the whole being so arranged as to form an appropriate ornament for the door.

Having fully described our design for Cook Stoves, that we claim as new therein and desire to secure by letters patent is; the ornamental design and configuration of Cook Stove plates, the same as herein described and shown in the annexed perspective drawing.
